UNITED STATES PATENT OFFICE

HENRY L. FINO, OF MILFORD, MASSACHUSETTS

STAKE RETAINER

Application filed February 28, 1929. Serial No. 343,310.

This invention relates to an improved retainer for a stake such as is used upon wagons, trucks, and similar conveyances.

Briefly, the invention comprises a novel metallic fixture including a socket for reception of the stake and a spring pressed retaining latch carried thereby.

In carrying out the invention I have evolved and produced a structure of this character which is characterized by unusual simplicity and durability in construction, and which is otherwise made to render it highly efficient, easy to manipulate, and otherwise well adapted for the purposes intended.

Other features and advantages will become more readily apparent from the following description and drawings.

In the drawings:

20 Figure 1 is an elevational view of the complete structure showing the stakes associated therewith.

Figure 2 is a vertical sectional view taken approximately upon the plane of the line 25 2-2 of Figure 1.

Figure 3 is a bottom plan view of the structure seen in Figure 1.

Figure 4 is a fragmentary perspective view of the metal faced stake.

30 In the drawings the reference character 5 designates generally the fixture or bracket. It comprises a single metal body including a substantially U-shaped portion 6 which functions as a socket or embracing strap for the stake 7. The reference character 8 designates an attaching flange on one side and 9 a similar attaching flange on the opposite side. Cooperable with the last named flange is a hollow box like portion 10 which functions

40 as a housing or casing for a latch 11. This latch is pivotally mounted on a horizontal pivot pin 12 and includes a laterally directed end portion 13 forming a retaining finger. This is adapted for removable reception in 45 a socket or keeper seat 14 formed in one side of the stake. In this connection it is to be observed that on this side of the stake is an embedded wear plate 15 having an opening therein in register with the socket. The latch 50 is pressed into place automatically under the

action of a suitably anchored spring 16. The spring surrounds the pivot pin as shown in Figure 1 and has one end bearing against the intermediate portion of the latch to swing the retaining finger normally into the socket. It 55 is to be observed that the casing 10 is formed at 17 to form what may be designated as a shoulder. This allows the latch to be engaged behind the shoulder to withdraw the finger from the keeper socket and to hold the 60 latch in a normally disengaged position as shown in dotted lines to the left in Figure 1.

In practice the fixture 5 is bolted through the medium of the flanges 8 and 9 on the body of the wagon thereby providing a socket 65 for removable reception of the lower metal faced end of the stakes 7. The stake is dropped down in place, the latch is released and allowed to snap into retaining position. The latch has movement in a direction at 70 right angles to its longitudinal axis. In other words, it may be moved on the pivot pin 12 in a direction against the tension of the spring in order that it may be engaged behind the shoulder 17 to hold it in released 75 position.

The simplicity of the construction is such to enable the reader to obtain a clear understanding of the invention after considering the detailed description in connection with 80 the drawings. Therefore, a more lengthy description is regarded unnecessary.

Minor changes in shape, size, and rearrangement of details coming within the field of invention claimed may be resorted to in 85 actual practice if desired.

Having thus described the invention, what I claim as new and desire to secure by Letters Patent is:—

As a new product of manufacture, a stake 90 retaining device of the class described comprising a body having a substantially U-shaped intermediate portion functioning as a retaining socket for removable reception of the stake, said body having an attaching 95 flange on each side of the socket, the body being also formed at the juncture of one side wall of the socket and the adjacent flange with a box like latch casing, a horizontal pivot bolt in said casing, a spring pressed latch 100

mounted on said pivot bolt, said latch being movable in a direction at right angles to its longitudinal axis, whereby to permit it to be slid longitudinally of the pivot pin, and said
5 casing being provided with an internal shoulder with which the shank portion of the latch is engageable, whereby to permit the latch to be retained in released position.

In testimony whereof I affix my signature.
